UNITED STATES PATENT OFFICE.

EDWARD T. BATES, OF BRIGHTWOOD, DISTRICT OF COLUMBIA, ASSIGNOR
OF ONE-HALF TO MELVILLE LINDSAY, OF SAME PLACE.

MUFFLER FOR SIGNAL-BELLS.

SPECIFICATION forming part of Letters Patent No. 400,821, dated April 2, 1889.

Application filed July 13, 1888. Serial No. 279,805. (No model.)

To all whom it may concern:

Be it known that I, EDWARD T. BATES, a citizen of the United States, residing at Brightwood, in the District of Columbia, have invented certain new and useful Improvements 5 in Mufflers for Signal-Bells; and I do hereby declare the following to be a full, clear, and exact description of the invention, such as will enable others skilled in the art to which it app-
10 pertains to make and use the same.

My invention relates to signal-bells, and has for its object the production of a means for modifying the sharp ringing sound produced by the bell. Persons who are required to have 15 a signal-bell in the room and in close proximity to where they are employed are greatly annoyed by the sharp sound of the bell. It is my purpose to so modify the tone of a bell as to relieve the ear and not impair the utility
20 of the bell.

The invention will be hereinafter described, and particularly pointed out in the claims.

In the accompanying drawings, which form part of this specification, Figure 1 represents 25 a front elevation of a signal-bell with my invention applied. Fig. 2 is a perspective of the muffler, and Fig. 3 is a vertical section of the muffler shown applied to the hammer of a bell.

30 Reference being had to the drawings and the letters thereon, A indicates a signal-bell, which may be of any approved kind and for any purpose, and may be operated in any manner—such as mechanically, pneumati-
35 ally, electrically, or by any desired means.

For the purpose of illustration I have shown the bell-hammer B operated by a rod having a rack, a, in its upper surface, with which the short arm b of the lever C, supporting the ham-
40 mer, engages. The hammer B is surrounded by a muffler, D, made of india-rubber of vari-
ous thicknesses to suit the size and kind of bell to which it is to be applied. In small

45 bells the rubber must be very thin to prevent the utility of the bell being destroyed, and its thickness can be graduated in proportion to the size of the bell and its hammer and the power of the medium used for striking the bell.

50 In cases of illness the door-bell frequently becomes a source of great annoyance to the sufferer, and various means are resorted to to muffle the bell. The muffler D meets the requirements of the case and provides a ready means for accomplishing the result desired. 55 The muffler is contracted at its end c, and secures itself in position by its elasticity. It may be made of various shapes to suit different styles of hammers, and may be made up in quantities, packed in boxes, and sold to 60 the trade as an article of manufacture.

I do not wish to confine myself to the use of rubber, as the muffler may be made of buck or chamois skin or other suitable material. Rubber is, however, preferred, for the reason 65 that its elasticity enables it to be stretched over the bell-hammer, and it requires no other appliance to secure it in place.

Having thus fully described my invention, what I claim is—

1. As a new article of manufacture, a hollow flexible muffler conforming in its configuration to that of a bell-hammer, adapted 70 to cover said hammer and to be retained in position by adhesion.

2. As a new article of manufacture, a hollow and elastic muffler having the configuration of a bell-hammer, contracted at one end and adapted to be retained in position by its own elasticity, substantially as described. 75

In testimony whereof I affix my signature in presence of two witnesses.

EDWD. T. BATES.
